UNITED STATES PATENT OFFICE.

EDWARD J. BIRTCHE RD, OF GENOA, WISCONSIN.

DESIGN FOR A PIE-FORK.

SPECIFICATION forming part of Design No. 27,820, dated November 9, 1897.

Application filed September 1, 1897. Serial No. 650,304. Term of patent 14 years.

To all whom it may concern:

Be it known that I, EDWARD J. BIRTCHE RD, a citizen of the United States, residing at Genoa Junction, in the county of Walworth and State of Wisconsin, have invented and produced a certain new and original Design for Pie-Forks; and I do declare the following to be a full, clear, and exact description of the invention, such as will enable others skilled in the art to which it appertains to make and use the same.

My invention relates to a design for a pie-fork.

My design relates to the entire configuration of the fork.

It relates particularly to the design for a pie-fork, as illustrated in the accompanying drawing, in which the figure is a perspective view of a pie-fork embodying my design.

The leading features of my design appear in the following description.

1 represents the approximately oval han-

dle, formed with an open panel, which may afford room for suitable letters or other ornamentation, and 2 represents the shank the 25 edges of which curve inwardly to about midway of its length and diverge to the blade portion 3, which is formed with the longitudinal tines 4 and the parallel blade 5, having an outer beveled cutting edge 6, with its 30 outer end terminating in the pointed teeth 7.

Having thus fully described my invention, what I claim as new and useful, and desire to secure by Letters Patent of the United States, is—

The design for a pie-fork substantially as herein shown and described.

In testimony whereof I hereunto affix my signature in presence of two witnesses.

EDWARD J. BIRTCHE RD.
